UNITED STATES PATENT OFFICE.

HARRY MENDELSOHN, OF WESTFIELD, NEW JERSEY.

STAMP-RACK.

1,146,893.

Specification of Letters Patent. Patented July 20, 1915.

Application filed March 17, 1913. Serial No. 754,856.

To all whom it may concern:

Be it known that I, HARRY MENDELSOHN, a citizen of the United States, and a resident of Westfield, in the county of Union and State of New Jersey, have made new and useful Improvements in Stamp-Racks, of which the following is a specification.

This invention relates generally to stamp racks and is directed to new and useful improvements in such articles.

The object of the invention is to provide a stamp rack adapted to hold a number of rubber stamps or similar articles.

An approved embodiment of the invention comprises a frame having an opening therein, there being a resilient member extending along one edge portion of the opening; suitable means are provided for maintaining the frame in any desired location.

In the accompanying sheets of drawings, wherein structures are shown embodying the inventive idea, similar characters of reference in the several views designating similar parts, Figure 1 is a perspective view showing the rack held in position on a desk by being secured to the under side of the top portion thereof; Fig. 2 is a similar view showing the rack secured thereto in a different position; Fig. 3 is a sectional view on the line 3—3 of Fig. 2; Fig. 4 is a similar view showing a modified construction; Fig. 5 is a similar view showing the relation of the parts when the stamp is entered into the rack; Fig. 6 is a sectional view on the line 6—6 of Fig. 2; Fig. 7 is a perspective view of a modified structure; while Fig. 8 is a sectional view on the line 8—8 of Fig. 7.

The preferred form of the inventive idea embodies a frame, which, as shown, comprises the sides 1 and ends 2; these sides and ends result from the provision of the opening 3, the dimensions of the parts mentioned being capable of variation in the production of racks of different sizes adapted to hold stamps of various sizes and in various numbers.

As shown particularly in Fig. 1 two of the racks are positioned, one above the other, on the top portion 4 of a desk, extending downwardly therefrom, the racks being held together by means of rods or equivalent elements 5; the number of racks occupying such a relation may be increased in order to take care of stamps of different sizes, in which event the widths of the openings 3 may vary.

As shown particularly in Fig. 2, the racks, either one as in this figure or a plurality as in Fig. 1 may be mounted on top of a desk or table 6 being supported in such position by the aforementioned rods 5; the particular manner of supporting the rack is, of course, immaterial.

Extending longitudinally of the edge portions of the opening 3 in the frame are resilient members 7 which may be made of rubber or similar material; in order to hold these members in position the sides 1 may be conveniently made of sheet material folded along a median line whereby a pocket 8 is formed into which the member is placed, the folded material being then compressed with consequent retention of the member therein; such construction is simple and affords a manner of manufacture which is low in cost. It is not essential that these resilient members extend along both edges of the said opening; as shown particularly in Fig. 4 one such member may be positioned adjacent one edge, the other edge being rounded or chamfered whereby passage of the handle 9 of the stamp or other article adjacent such edge is facilitated. In this figure the side 1^a is provided with an extension 1^b which may be folded as shown thereby closing the pocket formed by the bending of the material of which the side is made; a solid piece of material may be employed, if so desired, the edge portion thereof which comes adjacent the said opening being similarly shaped.

Referring now to Figs. 5 and 6 it will be seen that when the handle of the article is entered into the opening in the frame that the resilient member or members 7 are bent, whereby passage of the handle is permitted, these members returning to normal position after the portion of the handle of lesser width comes adjacent thereto, because of the nature of the material from which these members are made; the said members are of sufficient stiffness to support the articles (as shown in Fig. 2) after the reduced portions of the handles come into engagement therewith. Such manner of operation requires that the normal width of the opening in the frame be greater than the greatest width of the handle of the article, and that the distance which the said resilient member projects into the opening be such that the final width of the opening be less than the greatest width of such handle.

Various modified structures will suggest themselves to those skilled in the art; in Figs. 7 and 8 one modification is set forth which embodies the use of flexible and resilient members 10 adjacent the opening 3, which members are in the nature of springs of helical form and which have been flattened. The particular forms of the sides 1 and ends 2 of the frame are unchanged, 10 the pockets 8 in the sides receiving and retaining the said springs. The operation of these members 10 is not unlike that of the rubber members 7, since the entrance of a handle into the opening flexes certain turns 15 of the springs which operate in a manner analogous to the first mentioned members 7; while two springs are shown in the drawings it is, of course, clear that only one may be used as set forth when the preferred 20 form of the invention was being described. The material of which the parts of the frame is made is of no consequence so long as such part possesses the necessary rigidity for efficient use.

25 What I claim as my invention is—

1. A stamp rack comprising parts arranged to provide an elongated opening between them of a width sufficient to receive the stamp handles and of a length sufficient

to receive a plurality of stamp handles, one 30 of said parts having flexible resilient holding means extending longitudinally thereof and projecting into said opening, said holding means being adapted to yield to permit the ends of stamp handles to be passed 35 through the opening and serving to yieldingly hold handles which have been passed through the opening.

2. A stamp rack comprising in combination with a suitable support, a substantially 40 rectangular frame having end members and parallel side members, said side members being each composed of a metallic strip bent upon itself to provide a U-shaped channel and a resilient member disposed within each 45 of said channel members and having a portion extending laterally beyond the mouth thereof, said resilient members being secured throughout their entire length within their respective channel members.

50 In testimony whereof I have hereunto signed my name in the presence of two witnesses:

HARRY MENDELSONH.
